CLAIM

The ornamental design for a combined cordless iron and electric base and stand unit, as shown and described.

DESCRIPTION

FIG. 1 is a perspective view as seen from one side of a combined cordless iron and electric base and stand unit showing my new design, the stand being omitted for clarity of illustration only;

FIG. 2 is a perspective view as seen from the opposite side thereof;

FIG. 3 is a fragmentary perspective view as seen from one side of the iron, shown separately for clarity of illustration only;

FIG. 4 is a fragmentary bottom perspective view thereof;

FIG. 5 is a front perspective view of the stand, shown separately for clarity of illustration only;

FIG. 6 is a rear perspective view thereof;

FIG. 7 is a front perspective view of the assembled unit;

FIG. 8 is a rear perspective view thereof;

FIG. 9 is a rear perspective view of the electric base, shown separately for clarity of illustration only;

FIG. 10 is a front perspective view thereof;

FIG. 11 is a front perspective view of the stand, shown separately for clarity of illustration only;

FIGS. 12-22 are views of a second embodiment taken identically as the views of FIGS. 1-11;
